UNITED STATES PATENT OFFICE.

OTTO PORBECK, OF ST. LOUIS, MISSOURI.

JAPANNING-OVEN.

1,354,210.

Specification of Letters Patent. Patented Sept. 28, 1920.

Application filed October 4, 1919. Serial No. 328,426.

To all whom it may concern:

Be it known that I, OTTO PORBECK, a citizen of the United States, residing at St. Louis, Missouri, have invented a certain new 5 and useful Improvement in Japanning-Ovens, of which the following is a full, clear, and exact description, such as will enable others skilled in the art to which it appertains to make and use the same, reference 10 being had to the accompanying drawings, forming part of this specification.

My invention relates generally to ovens and more particularly to an oven of the portable type and in which radiated heat 15 is utilized for the baking of japan, enamel, lacquer, or the like upon metals or for the drying or baking of any material which during the drying process gives off combustible vapors.

20 The principal objects of my invention are, to provide a relatively simple and efficient oven which can be easily and cheaply manufactured; to provide an oven which can be economically and conveniently heated; to 25 provide for the thorough and uniform radiation of heat throughout the drying or baking chamber within the oven; to provide for the preheating of the air that circulates through the heating or baking chamber and 30 which is effective in carrying off the moisture and combustible vapors arising from the material being dried or baked; and, further, to provide a construction which 35 will wholly eliminate the danger of fires resulting from accidental ignition of the combustible vapors arising from the material being dried or baked.

With the foregoing and other objects in view, my invention consists in certain 40 novel features of construction and arrangement of parts, hereinafter more fully described and claimed, and illustrated in the accompanying drawings, in which—

Figure 1 is a top plan view of an oven 45 of my improved construction, portions thereof being broken away and in horizontal section.

Fig. 2 is a cross section taken approximately on the line 2—2 of Fig. 1.

50 Fig. 3 is an enlarged detail elevational view taken looking in the direction indicated by the arrow 3, in Fig. 1.

Fig. 4 is a front elevational view partly

in section of a modified form of my improved oven.

55

Fig. 5 is a horizontal section taken approximately on the line 5—5 of Fig. 4.

Fig. 6 is a detail section illustrating a modified construction of the bottom portion 60 of the oven.

65

Referring by numerals to the accompanying drawings and particularly the construction illustrated in Figs. 1 to 3 inclusive, 10 designates the bottom or base plate of the oven, and secured thereto in any suitable manner are a pair of side walls 11, a rear wall 12, and a front wall 13, and secured to the upper edges of these walls is a top 14. These walls and top are preferably made double and the intervening space is packed 70 with asbestos or analogous heat insulating material as designated by 15.

Extending upwardly from the bottom plate 10 and arranged parallel with and a short distance away from the lower portion 75 of each side wall 11 is a vertically disposed wall 16, the same extending from the front wall 12 to the rear wall 13 and extending from the top of each of these walls 16 toward the adjacent side wall 11 is a 80 horizontally disposed wall 17. These walls together with the adjacent portions of the bottom plate 10 and side walls 11 form elongated chambers 18 in the lower corners of the oven and where the oven is heated 85 with gas or liquid hydrocarbon, burner tubes such as 19 extend lengthwise throughout said chambers. These tubes preferably enter the oven through the front wall thereof and in order that the gas or liquid hydrocarbon 90 issuing from the jets of said burner tubes may be readily ignited to heat the oven, the front wall 13 is provided at the front ends 95 of the chambers 18 with openings 20 that are normally closed by small hinged doors 21. Openings such as 22 are formed through the front wall 13 immediately below the doors 21, said openings being for the purpose of admitting air to the chambers to support combustion of the gas or liquid hydrocarbon consumed therein.

100 Arranged in the lower inner corners of the chambers 18 are partitions 23 which, together with the adjacent portions of the partitions 16 and the bottom plate 10, in close longitudinally disposed air preheating

chambers 24, the same extending the entire length of the chambers 18 and the front ends of said air preheating chambers communicating with air inlet openings 25 that are formed in front wall 13.

Formed in the lower portions of the walls 16 are apertures 26 which permit the preheated air to pass from the chambers 24 into the lower portion of the drying chamber of the oven. This air is utilized for carrying off moisture arising from the material under treatment within the oven and said air and the combustible vapors arising from the material under treatment escape from the chamber through suitable outlets 27 that are located on the top 14.

Arranged within the drying chamber in the oven substantially parallel with and a short distance away from the side walls 11 are corrugated heat radiating walls 28, the lower edges of which are connected to the horizontally disposed partitions 17. The corrugations of these walls 28 are preferably horizontally disposed and secured to the inner faces of the side walls 11 and projecting into the corrugations of the heat radiating walls 28 are horizontally disposed baffle plates 29, such construction forming tortuous passages for the heated air traveling upwardly from the chambers 18.

The upper ends of the corrugated heat radiating walls 18 are connected to longitudinally disposed inverted U-shaped housings 30 and leading from the central portions of the latter inwardly to a central point on the top 14 are pipes 31 which communicate with an outlet pipe 32, the latter projecting through top 14. When this form of the oven is in service, burners 19 are lighted and the air heated within the chambers 18 travels upwardly through the tortuous passages provided by the corrugated walls 28 and baffle plates 29 and as a result, the corrugated walls 28 are heated to a relatively high degree and this heat is radiated throughout the entire chamber within the oven. This uniform radiation of the heat is very effective in drying coated work placed in the oven and which work is supported on suitable removable racks as illustrated by dotted lines A, in Fig. 2. The air which is heated by the burners in the chambers 18 and which supports combustion of the fuel ignited at said burners, is admitted through the openings 22 in front wall 13 and the air and products of combustion leave the upper portions of the tortuous passages and leave the oven through pipes 31 and outlet 32.

60 The air necessary to carry off the moisture and the like from the material being dried within the oven enters the openings 25 and after being preheated in the chambers 24 passes outwardly through apertures 26 and thence upwardly through the cham-

ber within the oven and this air and the moisture and vapors combined therewith discharges through outlets 27.

In the form of oven illustrated in Figs. 4 and 5, a chamber 33 is formed between the bottom plate 10^a and a horizontally disposed partition 34 which is located a short distance above said bottom plate and the side edges of which partition connect with the lower edges of the corrugated heat radiating walls 28^a.

Where the oven is to be heated with gas or liquid hydrocarbon, suitable burner tubes 35 are located in this chamber 33 and the air to support combustion and to be heated and utilized for carrying the heat upwardly through the side portions of the oven is taken into the chamber through an opening 36 in the lower portion of the front wall of the oven.

Located in the front wall immediately above this partition 36 and above the burner tubes is an opening that is normally closed by a door 37 which latter permits the burners to be readily lighted.

Located between the lower portions of the side walls of the oven and the lower portions of the corrugated walls 28^a are tubes 38 which admit air to the drying and baking chamber within the oven and which tubes are located above the ends of the chamber 33 in order that the air passing into the oven chamber may be effectually preheated.

In the modified construction illustrated in Fig. 6, a horizontally disposed partition 39 is arranged a short distance above the bottom plate of the oven, said partition being corrugated so as to provide channels 40 which extend from the front wall of the oven to the back wall thereof, there being openings in the front wall of the oven communicating with the front ends of said channels to permit the inlet of air. The tops of these channels are closed by plates 41 that are perforated as designated by 42, thus permitting the air to pass from said channels upwardly into the heating or baking chamber of the oven.

An oven of my improved construction is comparatively simple, can be easily and cheaply constructed, can be heated in any desired manner, but preferably by the combustion of gas, liquid hydrocarbon or fuel such as coke, is provided with relatively large heating surfaces, the same being arranged so as to uniformly radiate the heat throughout the drying or heating chamber, and the air that is taken into the heating or baking chamber to carry off the moisture and the like is thoroughly preheated prior to its entrance into said chamber.

It will be readily understood that minor changes in the size, form and construction of the various parts of my improved oven

can be made and substituted for those herein shown and described, without departing from the spirit of my invention, the scope of which is set forth in the appended claims.

5. I claim:

1. In an oven of the class described, a housing, a corrugated wall arranged within said housing and spaced apart from one of the walls thereof, and there being a chamber formed in the lower portion of the housing and communicating with the space between the wall of the housing and said corrugated wall.

15. In an oven of the class described, a housing, a corrugated wall arranged within said housing and spaced apart from one of the walls thereof, there being a chamber formed in the lower portion of the housing and communicating with the space between the wall of the housing and said corrugated wall, and there being an outlet leading from the space between the wall of the housing and said corrugated wall.

25. In an oven of the class described, a housing, a corrugated wall arranged within said housing and spaced apart from one of the walls thereof, there being a chamber arranged in the lower portion of the housing and communicating with the space between the wall of the housing and said corrugated wall, and there being an air pre-heating chamber located adjacent to said chamber.

35. In an oven of the class described, a housing, a corrugated wall arranged in said housing and spaced apart from one of the walls thereof, baffle plates arranged between said corrugated wall and the adjacent wall of the housing, and there being a chamber formed in the lower portion of the housing of the oven, which chamber has communication with the space between the corrugated wall and the adjacent wall of the housing.

45. In an oven of the class described, a housing, a corrugated wall arranged in said housing and spaced apart from one of the walls thereof, baffle plates arranged between said corrugated wall and the adjacent wall of the housing, there being a chamber in the lower portion of the housing of the oven, which chamber has communication with the space between the corrugated wall and the adjacent wall of the housing, and there being an air preheating chamber located adjacent to said chamber.

55. In an oven of the class described, a housing, a corrugated wall arranged in said housing and spaced apart from one of the walls thereof, baffle plates arranged between said corrugated wall and the adjacent wall of the housing, there being a chamber in

the lower portion of the housing of the oven, which chamber has communication with the space between the corrugated wall 65 and the adjacent wall of the housing, there being an air preheating chamber located adjacent to said chamber, the upper portion of the oven being provided with an air and vapor outlet, and there being an outlet leading from the upper portion of the space between the corrugated wall and the adjacent wall of the oven housing.

7. In an oven of the class described, a housing provided in its lower portion with 75 a chamber, a wall located within said housing adjacent to one of the walls thereof, the space between the wall of the housing and the adjacent inner wall having communication with said chamber, and means 80 for conducting air into the drying chamber within the oven, which means is located adjacent to the chamber in the lower portion of the oven housing.

8. In an oven of the class described, a 85 housing, a wall arranged within said housing and spaced apart from one of the walls thereof to form a heated air duct, baffle plates arranged in said heated air duct, and there being a combustion chamber located 90 in the lower portion of the oven and having communication with said heated air duct.

9. In an oven of the class described, a 95 housing, a wall arranged within said housing and spaced apart from one of the walls thereof to form a heated air duct, baffle plates arranged in said heated air duct, there being a combustion chamber located in the lower portion of the oven and having 100 communication with said heated air duct, and means located adjacent to the combustion chamber for preheating air and delivering the same into the baking chamber of the oven.

10. In an oven of the class described, a housing, a wall arranged within said housing and spaced apart from one of the walls thereof to form a heated air duct, baffle plates arranged in said heated air duct, there being a combustion chamber located in the lower portion of the oven and having communication with said heated air duct, means located adjacent to the combustion chamber for preheating air and delivering the same into the baking chamber of the oven, the upper portion of said oven being provided with an outlet, and the upper portion of the heated air duct being provided with an outlet.

In testimony whereof I hereunto affix my signature this 2nd day of October, 1919.

OTTO PORBECK.
